UNITED STATES PATENT OFFICE.

JEROME H. HENNESSEY, OF WASHINGTON, DISTRICT OF COLUMBIA.

INKING-ROLLER AND PROCESS OF MAKING SAME.

1,079,339.

Specification of Letters Patent. Patented Nov. 25, 1913.

Application filed May 31, 1912. Serial No. 700,791.

To all whom it may concern:

Be it known that I, JEROME H. HENNESSEY, a citizen of the United States, residing at Washington, in the District of Columbia, have invented certain new and useful Improvements in Inking-Rollers and Processes of Making Same, of which the following is a specification.

This invention especially relates to the manufacture of the ductor-rollers which are employed in printing presses to transfer ink from the fountain roller to the distributor-plate or roller. These ductor-rollers usually consist of a cylindrical metal core or body having gudgeons, upon which is a concentric cast layer of a composition of glue and glycerin.

The present invention relates to an improved process of making these rollers, and to a roller, such as is produced by the new process.

Referring to the accompanying drawings:—Figure 1 is an elevation of a portion of the completed roller; Fig. 2 is an elevation illustrating on a smaller scale the roller during process of manufacture; and Fig. 3 is an end elevation of the roller shown in Fig. 1.

In order to produce my improved roller, the body B consisting of a suitable composition, such as glue and glycerin, is cast about a metal core A in a cylindrical mold, in the usual way. When the composition has sufficiently solidified, the core with its cast roller thereon is removed from the mold. Rings C, C, are then slipped on the gudgeons D, D', each of these rings having a set-screw E for holding it fast to the gudgeons, and having on the periphery a number of pins F. A flexible strip H which may be of any suitable material, such as tape or leather, is then fastened at one end to the pins on one of the rings C and then wound tightly in a helical line about the roller, sufficient pressure and tension being exerted on the tape to cause it to make depressions on the surface of the roller body. The other end of the tape is then fastened to the pins F of the ring C on the gudgeon at the other end of the roller, and the roller thus tightly wrapped is left for a sufficient time to permit the roller body to acquire a permanent set. The tape is then removed and the roller will be found to have acquired a permanent set with a helical de-

pressed portion or valley G extending from end to end of the roller with a corresponding slightly raised helical portion between the depressions.

While I have described a particular means for securing the ends of the tape, obviously any other suitable clamping or securing means may be used.

The resulting article is a roller having a helical ink-applying surface with intermediate helical lower portions sufficiently depressed so as not to come into contact with the surface of the distributor-plate or roller to which the ink is to be applied.

It will be observed that the elevated ink-applying portion of the roller merges into the corresponding depression by curves whereby angular portions or sharp edges are avoided. Such sharp edges are liable to break off and leave projections or ragged portions which, in the use of the roller, tend to fill up openings in the type, such as in the letters o, b, e, q, d, etc. The rounded sides of the elevated ink-applying portion of the roller obviates this difficulty.

I am aware that a roller having a helical ink-applying surface is not new, such a roller being shown in my own Patent Number 905,182, patented December 1, 1908. While such rollers have been found to be effective in use, they are, owing to the comparatively large surfaces exposed at the sides of the depressed portions, liable to dry out or harden more rapidly than the solid cylindrical roller.

My present invention has all the advantages of both types of rollers, i. e., it has a massive substantially cylindrical body with comparatively shallow helical depressions in its surface; by which construction, the advantages of the helical ink-applying surfaces are retained, while the roller does not dry out or harden any quicker than would a cylindrical roller.

I claim:—

1. The process of making an inking roller which consists in casting the roller in cylindrical form, winding about said cylinder a tape in a helical line and under sufficient tension to cause a helical depression therein and allowing the so-wound roller to stand until the roller-material has acquired a permanent set.

2. An inking roller having thereon a helical ink-applying portion with a correspond-

ing shallow depression between the turns of the helix, such depression being only so deep as to avoid contact with the surface to which the ink is to be applied.

5. An inking roller having thereon a helical ink-applying portion rounded at the sides, with a corresponding shallow depression between the turns of the helix, such depression being deep enough to avoid contact

with the surface to which the ink is to be applied. 10

In testimony whereof I affix my signature in presence of two witnesses.
